UNITED STATES PATENT OFFICE.

JOHN C. NULL, OF DAYTON, OHIO, ASSIGNOR OF ONE-HALF TO CHARLES F. BRYANT, OF SAME PLACE.

ANTI-RATTLER FOR THILL-COUPINGS.

SPECIFICATION forming part of Letters Patent No. 336,150 dated February 16, 1886.

Application filed October 28, 1885. Serial No. 181,150. (No model.)

To all whom it may concern:

Be it known that I, JOHN C. NULL, a citizen of the United States, residing at Dayton, in the county of Montgomery and State of Ohio, have invented a certain new and useful improvement in Anti-Rattlers for Thill-Couplings; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

15 My invention relates to improvements in anti-rattlers for thill-couplings; and it consists of a flat piece of steel suitably bent and inserted between the thill-iron and the jack-clip, as will be fully hereinafter set forth.

20 The object is to so form an anti-rattler that it will be secure within its bearings. I attain the object by the mechanism illustrated in the accompanying drawings, in which—

Figure I is a side view of a thill-coupling 25 with the anti-rattler in position. Fig. II is a side view of the anti-rattler.

C is the thill-iron, and A the jack-clip, which are connected by the usual form of bolt.

B, Fig. I, shows the anti-rattler in position 30 between the thill-iron and the front surface of the jack-clip. The front bearing-surface is circular, and rests against the thill-iron. The back is curved and bears against the jack-clip, and a projection of the back at the top extends 35 over a shoulder of the said clip.

At B, Fig. II, is shown the form of the anti-rattler before its insertion, which slightly compresses the same. The steel plate is bent upon itself, the front having the two curves *s* and *u*, at the junction of which a prominence is 40 formed which prevents the anti-rattler from being raised from its position.

v is the curved back, at the top of which is a bend backward, *t*, which engages a shoulder of the jack-clip, and thereby prevents the same 45 from being forced down out of position. The part *w* prevents substances falling within, which would impair the spring of the metal.

I am aware that steel plates have been bent and placed between the thill-iron and the jack-clip to serve as an anti-rattler, and I therefore claim only the specific form herein set forth. 50

Having fully described my invention, what I claim, and desire to secure by Letters Patent, is—

An anti-rattler for thill-couplings formed of 55 steel plate of uniform width bent upon itself, with double curves on its front face and a backward curve or projection at the top, and from this point a forward projection, substantially as shown and described.

In testimony that I claim the foregoing as my own I affix my signature in presence of two witnesses.

JOHN C. NULL.
